UNITED STATES PATENT OFFICE.

ABE LINCOLN CUSHMAN, OF CONCORD, NEW HAMPSHIRE.

FIELD-MAGNET FOR DYNAMO-ELECTRIC MACHINES.

No. 893,835.

Specification of Letters Patent.

Patented July 21, 1908.

Application filed March 18, 1907. Serial No. 362,914.

To all whom it may concern:

Be it known that I, ABE LINCOLN CUSHMAN, a citizen of the United States, and resident of Concord, in the county of Merrimack and State of New Hampshire, have invented new and useful Improvements in Field - Magnets for Dynamo - Electric Machines, of which the following is a specification.

10 My invention relates to field magnets for dynamo electric machines and its object is to provide the improvements hereinafter set forth in the construction of field cores, wherein enlarged or extended pole tips are 15 provided, and wherein only so much of the pole tip is made removable as is necessary to allow the field windings to be slipped on and off the pole pieces ready wound, thus eliminating cross cuts in the pole piece so 20 far as possible.

My invention though applicable to field magnets generally, is especially intended for use in connection with variable speed motors, in which the speed variation is 25 effected by the weakening and strengthening of the fields.

Among other objects accomplished by my invention, it is its purpose to provide a removable pole tip which will admit of placing 30 the field windings upon the pole pieces ready wound, of such construction that cross cuts between the body of the pole piece and the removable pole tip shall be eliminated so far as possible; that the retaining means for the removable pole tip shall be located outside of the area of the field windings; and that the cuts between the removable part and the body of the pole piece shall be arranged approximately parallel, or 35 at an acute angle, with the axis of the pole piece, whereby the area of the cut crossed by the lines of force shall be increased thus reducing its reluctance; by reason of all of 40 which features obstructions are removed 45 which would tend to cause eddy currents to flow in the pole pieces to heat the poles or distort the fields and increase the reluctance of the magnetic circuit.

While my invention is applicable to field magnets generally, I believe that in its best form it is to be employed in laminated field magnets and I will therefore address my description to a laminated magnet.

In the accompanying drawing which illustrates an embodiment of my invention, is

shown one lamina of a laminated field magnet containing my invention.

The ring 1 is provided with the several pole pieces 2 herein shown as projecting inwardly from the magnetic yoke at intervals 5 of 90°. Each pole piece 2 is made with a longitudinal recess or pocket 3 extending throughout the length of the pole piece and into the magnetic yoke. A removable L-shaped section 4 has a shank 5 fitting in the longitudinal pocket 3; and the toe 6, which forms one end of an extended or flaring pole shoe. The other end 7 of the extended or flaring pole shoe is made integral with the body of the pole piece 2. This extended 10 pole shoe prevents the abrupt entrance of the armature wires into the field and insures 15 sparkless commutation when the fields are weakened to increase the speed of the motor. Between either end 6 and 7 of the flaring pole 20 shoe, and the body of the pole piece 2, is provided the notch 8 to concentrate the 25 lines of force near the tip of the pole piece. Near the end of the shank 5 of the removable 30 section 4 of the pole piece is a retaining bolt 35 for securing the removable section in position. This retaining bolt, it will be seen, is 40 back of and outside of the area of the field windings. It will also be observed that substantially all cross cuts as well as the retaining 45 means itself are eliminated from the area of the field windings, and that the cuts between the body of the pole piece and the removable section of the pole piece are approximately 50 parallel, or at an acute angle, with the axis of the pole piece, the large area of the cut thus provided reducing the reluctance 55 of the magnetic circuit where it crosses said cut. The cut on the side of the removable section toward the pole tip 7, it will be 60 seen, does not intersect the lines of force in 65 that side of the pole piece at all. This result is more perfectly accomplished by the above 70 described device than in the construction 75 shown in my pending application, Serial No. 100 259,293 wherein both ends of the flaring pole shoe are made movable with the removable section, and at the same time the device is 105 equally well adapted for slipping the field windings on and off the pole pieces readily as when both ends of the pole shoe instead 110 of one end are made removable.

What I claim and desire to secure by Letters Patent is:

1. In a field magnet, a pole piece having

- a longitudinal recess or pocket extending throughout the length of the pole piece, a removable polar section fitting into said recess or pocket, enlarged or extended pole 5 tips, one on either side of the pole piece to form a flaring pole shoe, one of said extended tips being integral with the pole piece and the other of said extended pole tips being integral with the removable section, a magnet 10 winding upon said pole piece, and means located back of the area of the magnet winding to secure said removable section to the pole piece.
2. In a field magnet, a pole piece having 15 a longitudinal recess or pocket extending throughout the length of the pole piece, a removable polar section fitting into said recess or pocket, enlarged or extended pole tips, one on either side of the pole piece to 20 form a flaring pole shoe, one of said extended pole tips being integral with the pole piece, and the other of said extended pole tips being integral with the removable section, lateral notches being provided between the pole tips 25 and the body of the pole piece, and means to secure said removable section to the pole piece.
3. In a field magnet, a pole piece having a longitudinal recess or pocket extending 30 throughout the length of the pole piece, said pole piece being provided at one side with an extension integral with the pole piece, to

form one end of an extended or flaring pole shoe, an L-shaped removable section, the shank of which fits in said recess and the toe 35 of which forms the other end of the extended or flaring pole shoe, a magnet winding upon said pole piece, and means located back of the area of the magnet winding near the end of the shank for securing said removable section in position.

4. In a field magnet, a pole piece having a longitudinal recess or pocket extending throughout the length of the pole piece, said pole piece being provided at one side with an 45 extension integral with the pole piece, to form one end of an extended or flaring pole shoe, and with a lateral notch between said pole shoe, and the body of the pole piece, an L-shaped removable section, the shank of 50 which fits in said recess and the toe of which forms the other end of the extended or flaring pole shoe, a lateral notch being provided between the pole shoe of said L-shaped piece and the adjacent end of the body of the pole 55 piece, and means for securing said removable section in position.

Signed by me at Boston, Massachusetts this 16th day of March 1907.

ABE LINCOLN CUSHMAN.
